UNITED STATES PATENT OFFICE.

WILLIAM KURZENKNABE, OF CHICAGO, ILLINOIS.

DESIGN FOR A TAP-SOLE.

SPECIFICATION forming part of Design No. 25,757, dated July 7, 1896.

Application filed March 9, 1896. Serial No. 582,483. Term of patent 14 years.

To all whom it may concern:

Be it known that I, WILLIAM KURZENKNABE, a citizen of the United States, and a resident of Chicago, in the county of Cook and State of Illinois, have invented and produced a new and original Design for Tap-Soles, of which the following is a specification, reference being had to the accompanying drawings, forming a part thereof.

10 The leading feature of my design consists in its peculiar configuration and outline, which comprises two substantially straight and parallel sides and two curved sides, which give to the tap-sole a characteristic and distinguishing appearance.

15 The design is illustrated in the accompanying drawings, in which—

Figure 1 is a top plan view of a tap-sole, showing my design; and Fig. 2 is a perspective view of the tap-sole.

The tap-sole is substantially oblong in shape, and it is provided with the two straight sides A, B, which are substantially parallel with each other. The other sides of the tap-sole are curved, the outline of one side C ²⁵ being concavo-convex and the outline of the other side being substantially convex, all as shown in the accompanying drawings.

The design provides a tap-sole which presents to the eye a distinguishing and characteristic appearance, varying from other designs of tap-soles particularly in having two straight sides and two curved sides.

What I claim is—

A design for a tap-sole, substantially as shown and described.

WILLIAM KURZENKNABE.
